BLADE ASSEMBLY FOR DISCONNECT SWITCHES

Filed July 26, 1951

UNITED STATES PATENT OFFICE

2,658,964

BLADE ASSEMBLY FOR DISCONNECT SWITCHES

Gustave E. Heberlein, Bryn Mawr, Pa., assignor, by mesne assignments, to I-T-E Circuit Breaker Company, Philadelphia, Pa., a corporation of Pennsylvania.

Application July 26, 1951, Serial No. 238,613

5 Claims. (Cl. 200—48)

1

My present invention relates to disconnecting switches and more particularly it relates to the blade assembly of the disconnect switch of the type shown in patent application Serial No. 145,389.

This switch has an angularly movable contact arm rotatably mounted on a base or terminal. This contact arm includes a blade which rotates around its longitudinal axis into high pressure engagement with stationary contacts. To permit this rotation, while maintaining a good current path between the rotating blade and the angularly movable portion thereof, a current carrying connection comprising threadedly engaged contact elements is used. This connection is of the type generally disclosed in application Serial No. 145,389, the present invention being a modification of that shown in the said application.

The primary object of my invention is, therefore, to provide a current conducting connection between the rotatable blade and the angularly movable member on which it is mounted.

Another object of my invention is the provision of a novel weatherproof efficient current carrying connection between the blade portion of the contact arm and the hinge casting of the disconnect switch.

Another object of my invention is the provision of spring loaded contacts at the connection between the angularly movable hinge casting and the rotatable blade itself so arranged that the contacts are always in engagement, thereby simplifying the provision of means for excluding foreign matter from the contacts and thereby preventing corrosion.

A further object of my invention is the provision of a garter spring to maintain the contact surfaces of the hinge casting and of the suitable blade into high pressure engagement.

These and many other objects of the invention will become apparent in the following description and drawings in which:

Figure 1 is a cross-sectional view of the disconnect switch incorporating this invention.

Figure 2 is a cross-sectional view of the hinge casting and switch blade of this invention showing the contacting fingers.

Figure 3 is a cross-sectional view of a modified version of the conducting joint of Figure 2.

Referring now to Figure 1, I have here shown a disconnect of the type disclosed in application Serial No. 145,389, filed February 21, 1950 in which the disconnect switch is mounted on the base 11 which is a suitable longitudinal struc-

2

tural support, in this case shown horizontally arranged for a horizontally or upright mounted disconnect switch.

The base 11 has secured thereto in any suitable manner as by the insulator spacers 12 and 13 the stationary upright supporting posts 14, 15 on the upper portions of which are mounted insulators 16, 17.

Base 11 is also provided with the bearing 20 appropriately secured thereto in any suitable manner as by the bolts 21 and carrying the rotatable vertical shaft 22 to the upper end of which is keyed the insulator 23 for rotation with the vertical shaft or post 22.

Below insulator 23 there is keyed to the shaft 22 the crank 30 secured thereto in any suitable manner as by the bolts 31 connected to the flange or crank plate 32. Bolts 21 which secure the bearing 20 in position also secure the stop plate 34 in position, the stop plate being provided at opposite ends with the adjustable stops 36, 37 which engage at either end with the stop 38 on the operating crank 30.

While stops 36, 37 are herein provided, the construction and operation of my novel switch is such that it may operate properly without the stops at individual poles; in such case, the stops would be provided at the operating means for the entire switch.

Where stops are eliminated at all points, then the switch may be operated by crank 30 to close and then open by a single continuous movement in one direction to establish a contact momentarily and then break it.

Shaft 22a extends above the insulator 23 as effectively a continuation of vertical shaft 22, being, however, spaced therefrom by insulator 23. Crank 40 at the upper end of shaft 22a is preferably integral therewith and, therefore, rotates therewith.

Crank 40 extends horizontally or at least parallel with the base supporting structure 11 and rotates in the horizontal plane. Crank 40 is shown herein as tubular although it may have any desired cross-section consistent with the mechanical loads imposed thereon. The outer end of crank 40 is flattened at 41 and is provided with a circular opening 42 through which pin 43 may pass.

A clevis member 44 receives extension 41, connection being made by pin 42. Clevis 44 is integral with the threaded extension 50 which enters into the tapped opening 51 in the forked link 52. The threaded extension 50 is so arranged that as the threaded extension 50 rotates with

respect to the forked link 52 and its tapped opening 51, it has linear movement with respect thereto.

Forked link 52 has a pair of arms 54 at the ends opposite the tapped opening 51 which are secured to the blade crank 61 of sleeve casting 62 by pin 60a. The blade support sleeve casting 62 carries the tubular switch blade 63 secured therein and rotatable therewith.

The outer end of the tubular switch blade is flattened at 64 (Figure 1) and is provided with appropriate contacts 65 engageable with the stationary contact jaws 66.

The blade support sleeve casting 62 is mounted for rotation around its longitudinal axis on an extension of the hinge casting 70.

The particular joint utilized for this mounting constitutes the essence of the present invention and will be discussed in detail below.

The hinge casting 70 is in turn rotatably mounted by the hinge bearings indicated generally at 72 on the forked frame casting 73. The frame casting 73 has a horizontal section 74 secured in any suitable manner as by the bolts 75 to the top of insulator 16.

The sides 76 extend back to the solid portion 77 which is provided with an opening 78 appropriately recessed to form a bearing for crank 40 and its shaft.

The solid portion 77 of the base casting 62 then extends beyond to form the terminal 80 to which appropriate leads may be connected.

The stationary contact 66 comprises the plurality of contact blades 90, 91 on each side biased toward each other by the spring support members 92, 93 and so arranged that when the blade 65 enters at an angle to the horizontal position during the closing operation it will clear the blades 90 on each side.

These contact members are so arranged, however, that when the blade is rotated from the open to the closed position the blade 65 in turning to the horizontal position will spread the contacts 90 and 91 on each side against the tension of springs 92 and 93, creating the desired contact pressure.

The spring blades 92, 93 are current conducting and are connected in any suitable manner as by the bolts 98 to the base plate 99, which in turn is mounted in any suitable manner as by bolts 100 at the top of insulator 17.

The base 99 of stationary contact structure 66 has an extension 101 which serves as a terminal block or connecting member.

Thus, when the disconnect switch is in the closed position of Figure 1, current enters the terminal 80, passes through the frame casting 73 to the hinge bearing 72, then through the current carrying connection in the hinge bearing 72 to the hinge casting 70; from the hinge casting 70 to the contact blade 63, then through the contact 65 on the contact blade 63 to the stationary contact elements 90, 91, and then through the base 99 to the terminal extension 101.

The conducting joint which constitutes the current carrying connection between the hinge casting 70 and the blade 63 is shown specifically in the cross-sectional view of Figure 2. A modification of this joint is shown in cross-section in Figure 3.

Referring first to Figure 2, the blade section 63 is a hollow metallic member extended back inside sleeve 62 which carries the blade crank 61. Sleeve 62 is rotatably mounted on the substantially cylindrical extension 205 of the hinge casting 70.

casting 70 by the rotatable interengagement of nut 255 of blade 63 with threaded part 206 of extension 205 of the hinge casting 70.

The interior of sleeve 62 is provided with an annular recess 201 at the point of engagement of the sleeve 62 with extension 200 of the hinge casting 70 to receive a weather-proofing gasket 207.

Adjacent the inner end of extension 205 a highly conductive cylindrical contact section 210 is mounted on appropriate material and secured to the cylindrical extension 205.

A plurality of contact fingers 216 are secured on a suitable way, for instance by brazing, to one end section of the blade tube 63. The contact side 213 of each of the contact fingers 216 is provided with a contact button 214 engaging the cylindrical contact 210. Where necessary for adequate contact pressure, a greater spring 215 is placed in a suitable annular recess 212 of the tube 62 so that it surrounds the contact fingers 216 at their ends 213 driving the contact buttons 214 into close continuously engaged current carrying engagement with the annular contact ring 210 of the hinge casting 70.

It is thus seen that the contact blade 63 may readily rotate around its longitudinal axis while an efficient continuously engaged current carrying engagement exists between contact blade 63 and the casting 70.

Thus, the current flows from stationary contact 66 through the movable contact 65, the contact blade 63, the contact fingers 216, contact buttons 214, the contact ring 210, to the casting 70 and then through the hinge contacts 72 to the base member 73 to the opposite terminal 80.

The necessity for flexible or extension connection is obviated. All current carrying connections are completely housed, sealed and weather-proofed. The weatherproofing for this conducting joint comprises the solid sleeve 62, the weatherproofing gasket 207 in annular recess 201 and the method of securing of the blade 63 to the sleeve 62.

To secure the blade 63 to the sleeve 62 a suitable method is used, for instance, that shown in the above-mentioned patent application Serial No. 145,389.

A modification of this conducting joint is shown in Figure 3. The blade section 63 is a hollow metallic member extended back inside sleeve 62 which carries the blade crank 61. Sleeve 62 is rotatably mounted on the substantially cylindrical extension 305 of the hinge casting 70 by the rotatable interengagement of nut 355 of blade 63 with threaded part 306 of extension 305 of the hinge casting 70.

The extension of sleeve 62 is provided with an annular recess 301 at the point of engagement of the sleeve 62 with extension 300 of the hinge casting 70 to receive a weatherproofing 307.

Two highly conductive cylindrical contact sections 310 and 311 are mounted on appropriate material and secured to the cylindrical extension 305, one adjacent the inner end of extension 305 and the other adjacent the threaded part 306 of extension 305.

Two sets of contact fingers 316 and 317 are secured in a suitable way, for instance, by brazing on the end of blade 63, one set 316 to make electrical contact with contact ring 310 and the other 317 to make electrical contact with contact ring 311.

The contact side 312 of each of the contact fingers 316 and the contact side 313 of each of

the contact fingers 317 are made of a highly conductive metal mounted in a suitable way on each finger of set 316 and 317.

Where necessary for adequate contact pressure, a garter spring 314 is placed in a suitable annular recess 318 of sleeve 62 so that it surrounds the contact fingers 316 at their ends 312 driving these highly conductive ends 312 into close continuously engaged current carrying engagement with the annular contact ring 310 of the hinge casting 70.

In this modification the addition of another set of fingers 317 and garter spring 320 makes the conducting joint a much more efficient current carrying connection.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A switch having a movable contact arm and a frame; said contact arm comprising an angularly movable hinge member mounted on said frame and a blade member mounted on said hinge member for rotation about its longitudinal axis; a current carrying connection between said blade and said hinge member; said current carrying connection comprising a plurality of contact fingers secured to said blade and extending substantially parallel to the axis thereof; and a contact ring on said hinge member in a plane substantially normal to the axis of the blade; the contact fingers engaging said ring; said contact fingers being biased toward said contact ring on said hinge member; means sealing said current carrying connection.

2. A switch having a movable contact arm and a frame; said contact arm comprising an angularly movable hinge member mounted on said frame and a blade member mounted on said hinge member for rotation about its longitudinal axis; a current carrying connection between said blade and said hinge member; said current carrying connection comprising two pluralities of contact fingers secured to said blade and extending substantially parallel to the axis thereof; and two contact rings on said hinge members in planes substantially normal to the axis of the blade; each plurality of said contact fingers engaging one of said contact rings to permit rotational movement of said blade with respect to said hinge while maintaining permanent contact engagement; said contact fingers being of a current carrying resilient material; said blade comprising a rigid tubular member; means biasing said pluralities of contact fingers toward said contact rings on said hinge member.

3. A switch having a movable contact arm and a frame; said contact arm comprising an angularly movable hinge member mounted on said frame and a blade member mounted on said

hinge member for rotation about its longitudinal axis; a current carrying connection between said blade and said hinge member; said current carrying connection comprising two pluralities of contact fingers secured to said blade and extending substantially parallel to the axis thereof; and two contact rings on said hinge members in planes substantially normal to the axis of the blade; each plurality of said contact fingers engaging one of said contact rings; said contact fingers being of a current carrying resilient material; said blade comprising a rigid tubular member; means biasing said pluralities of contact fingers toward said contact rings on said hinge member; means sealing said current carrying connections.

4. A switch having a movable contact arm and a frame; said contact arm comprising an angularly movable hinge member mounted on said frame and a blade member mounted on said hinge member for rotation about its longitudinal axis; a current carrying connection between said blade and said hinge member; said current carrying connection comprising two pluralities of contact fingers secured to said blade and extending substantially parallel to the axis thereof; and multiple contact rings on said hinge members in planes substantially normal to the axis of the blade; each plurality of said contact fingers engaging one of said contact rings; said contact fingers being of a current carrying resilient material; said blade comprising a rigid tubular member; means biasing said pluralities of contact fingers toward said contact rings on said hinge member; means sealing said current carrying connections.

5. A disconnect switch having a movable contact arm and a frame, said movable contact arm having rotational movement about its longitudinal axis and annular movement, said movable contact arm comprising a blade member and a hinge member, said hinge member positioned within said blade member, a current carrying connection between said blade and said hinge member, said current carrying connection comprising a plurality of resilient contact fingers permanently secured to said blade and extending substantially parallel to the axis thereof; a contact ring concentric with said hinge member and permanently secured thereto, said resilient contact fingers engaging said contact ring to permit rotation of said blade with respect to said hinge member, and a weather proofing gasket at said hinge to exclude foreign matter from the contacts and thereby prevent corrosion.

GUSTAVE E. HEBERLEIN.
